UNITED STATES PATENT OFFICE.

TURNER BYRD, OF LANSING, MICHIGAN.

EAVES-TROUGH.

1,398,415.

Specification of Letters Patent. Patented Nov. 29, 1921.

Application filed September 27, 1920. Serial No. 412,927.

To all whom it may concern:

Be it known that I, TURNER BYRD, a citizen of the United States, residing at Lansing, in the county of Ingham and State of Michigan, have invented a new and useful Eaves-Trough, of which the following is a specification.

This invention relates to a method of repairing eaves troughs or the like, and it is the object of the invention to provide a method of repair for restoring leaking eaves troughs, thereby obviating the necessity of replacing the eaves troughs.

The method also includes positioning lining strips in the trough to be repaired, together with means for securing the same in such position against displacement.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a plan view of a trough showing the same as having been repaired, in accordance with the present invention.

Fig. 2 illustrates a sectional view taken on line 2—2 of Fig. 1.

Fig. 3 illustrates a sectional view taken on line 3—3 of Fig. 1.

Referring to the drawing in detail, the reference character 5 designates a conventional form of eaves trough to be repaired, the eaves trough being provided with the usual discharge opening to permit water to flow into the down spout 6, which has connection with the eaves trough in the usual manner.

To repair the eaves trough, a plurality of strips of water-proofed material indicated by the reference character 7, are positioned within the trough, the strips being of any suitable length and having their forward edges curved as at 8, the adjacent ends of the strips overlapping each other as indicated more particularly by Fig. 2 of the drawing.

It might be further stated however that these strips 7 are capable of being flexed transversely of their lengths to permit the same to curve and conform to the curvature of the eaves troughs in which the same are positioned.

These strips 7 are secured within the eaves troughs as by means of the flexible securing members 9, each of which includes a length of wire bent adjacent to one end thereof to conform to the shape of the eaves troughs, one extremity of the wire being formed into a hook indicated at 10 to accommodate the eye 11, formed at the opposite extremity of the eye, there being provided a central hanging arm 12 also formed integral with the length of wire, whereby the trough may be supported under the eaves of a building.

As shown by the drawing, the securing members are positioned on the eaves trough at points adjacent to the overlapping ends of the section 7, so that the main or body portions of the securing members will contact with the upper edges of the member 7 to retain the same in the trough.

To insure against water entering between the members 7 and the trough, a water-proofing material is applied to both surfaces of the member 7, whereupon the same are positioned in the trough and secured by means of the securing members 9.

Having thus described the invention, what is claimed as new is:—

In an eaves trough, strips of water-proofed material positioned within the trough, said strips having their adjacent ends overlapping, a securing member including a length of wire positioned around the trough adjacent to the overlapped ends of the strips, the length of wire having a hook member formed at one end and having an eye formed intermediate its ends, said eye adapted to accommodate the hook member, and a hanging arm forming a part of the securing member.

In testimony that I claim the foregoing as my own, I have hereto affixed my signature in the presence of two witnesses.

TURNER BYRD.
